UNITED STATES PATENT OFFICE.

GEORGE C. THOMAS, JR., OF ELIZABETH, NEW JERSEY, ASSIGNOR TO THE THOMAS & BETTS CO., OF ELIZABETH, NEW JERSEY, A CORPORATION OF NEW JERSEY.

ADAPTER FOR CONNECTING DEVICES.

Application filed May 4, 1921. Serial No. 466,781.

To all whom it may concern:

Be it known that I, GEORGE C. THOMAS, Jr., a citizen of the United States, residing at Elizabeth, in the county of Union and State of New Jersey, have invented certain new and useful Improvements in Adapters for Connecting Devices, of which the following is a specification.

My invention relates to devices for connecting electrical conduits, connectors, cables or the like to electrical outlet boxes and the like, and more particularly relates to devices, generally called adapters, which may be used in connection with openings in outlet boxes, or the like, to enable a connector, or conduit, or cable of a smaller size than that of the opening to be inserted and secured within the opening.

Generally, to position a cable through the hole of an outlet box a connector or conduit of a size corresponding to the size of the opening is used, and a large variety of connectors and conduits of different sizes are usually kept on hand so that one of the proper size may be available for use with the opening in question. One of the objects of my invention is to provide a device or attachment adapted to be associated with a connector or a conduit or cable and an opening in an outlet box, or the like, and whereby such element may be readily and easily inserted and firmly secured in the desired position within the opening. For example, by means of my attachment a connector, which without my attachment is intended to fit a half inch opening, may readily be inserted and secured within an opening of larger size, such as three-quarters of an inch or one inch. Accordingly, by the use of my invention the number of different styles and sizes of connectors or conduits which must be manufactured and kept on hand may be greatly reduced. A further object of my invention is to provide an adapter comprising a minimum of parts for connecting devices, and an adapting device which may be inexpensively manufactured and is adapted to be easily associated with an opening and a connector or other element, and effectively aids in securing the connector or other element within the opening. Another object of my invention is to provide an adapter of the character above described comprising a washer and means for permitting the washer to be easily and readily mounted

upon the threaded neck of a connector, and at the same time, when so positioned is adapted to retain this part in position thereon so that it may not readily fall from or slide off the connector during the handling of the adapter, before or after the connector is mounted in the opening.

My improved adapter includes a member, preferably of annular shape, having an inside periphery sufficiently larger than the neck of a connector, or other element, to permit of its being easily positioned on such element, and having an outside periphery larger than the size of the opening within which the connector or other element is to be placed and secured. This annular member is adapted on one side to engage abutment means on the connector or other element, and on its other side to engage against a side of the wall about the opening. This annular member is provided with an inner portion, annular or otherwise, which is adapted to seat between the periphery of the wall opening and the periphery of the connector or other element, placed in the opening. A lock nut, or equivalent device, engaging the neck of the connector or other element, on the opposite side of the wall will, when properly adjusted, secure the smaller sized connector or other element, firmly in the desired position within the wall opening. When the annular member is provided with a transverse split the adjustment of the lock nut or other locking means will cause the annular member to expand and will then force the inner portion of the annular member into firmer binding engagement with the wall about the opening. I also provide a thread, or one or more small projections, extending sufficiently inwardly of the inner periphery of the annular member to engage between the threads on the neck of a connector, so that, when the annular member is positioned thereon, the annular member will not be apt to fall off during the handling of the parts prior to or after their association with the opening.

In order that my invention may be more clearly understood attention is hereby directed to the accompanying drawings forming part of this application and illustrating certain embodiments of my invention. In the drawings Fig. 1 represents a vertical section showing one form of my invention associated with an electrical connector and

mounted in position through an opening in a wall, the parts of the adapter and the wall being shown in section; Fig. 2 is an end view of my invention mounted upon a connector, the neck of the connector being shown in section; Figs. 3, 4, 5, 6 and 7 are views similar to Fig. 1 and illustrate respectively different embodiments of my invention with the annular member formed in certain various possible shapes.

Referring to the drawings, the connector 1 is of a well known form and has the usual neck 2 provided with external screw-threads 3. At the rear of the screw-threaded neck 15 2 is the peripheral flange 4, of greater diameter than that of the threaded neck, and the usual clamping ring 5 whereby a cable or conduit may be attached to and held by the connector in the usual manner.

20 6 indicates a wall of an outlet box or the like, and 7 indicates an opening in the wall through which it is desired that the connector be mounted. It is to be noted that the neck 2 of the connector is shown to be considerably smaller than the size of the opening 7 so that the function of my improved adapter may be appreciated more clearly. My improved device whereby this undersized connector may be mounted in the 25 opening 7 is illustrated in Figures 1 and 2 as comprising a ring 8 which may be of metal or other suitably rigid material and is preferably split transversely, as at 17. The inner periphery 9 of this ring is approximately the size of the threaded neck 2 of the connector and the outer portion of the ring is larger than the opening 7. The ring 8 at one side 11 is flattened and abuts against the flange 4 of the connector. The 30 opposite side 12 of the ring 8 at its outer portion, is also flattened and abuts against the wall surrounding the opening 7. Below flat surface 12 is an inner portion comprising an annular shank 13 extending axially beyond the side 12 and entering the opening 7 of the wall so as to be seated therein between the periphery of the opening 7 and the neck 2 of the connector. When the above mentioned parts have been so positioned the connector is prevented from 35 undesirably moving about laterally in the opening 7. To secure the connector firmly in place, a nut 14, having a larger diameter than that of the opening 7, is adjusted upon the threads 3 of the neck 2 of the connector until the wall 6 is firmly clamped between the nut 14 and the side 12 of member 8. When the parts have been properly positioned all the parts will be securely and 40 firmly fastened in the desired position, with flange 4 of the connector abutting the annular member 8 and shank 13 of that member seated within the opening 7 between the walls 6 and the neck 2 of the connector.

45 When member 8 is split transversely, as a

17, the clamping together of the elements will urge this member to spread and thus tend to cause shank 13 to bind more firmly against the periphery of the wall opening. This spreading effect on the member 8 is especially noticeable when it presents a tapered surface to the abutment means, as in the type shown in Figs. 3, 5 and 6. The spreading of the washer is effected in any event by the taper provided by the rounded shoulder 4.

It has been found that when the annular member 8 has a smooth, interior surface this member is apt to slip off the neck 2 of the connector during its handling, thus causing the inconvenience and delay of recovering and restoring this part to its proper place. To prevent or restrain annular member 8 from so slipping from the neck of the connector, I provide one or more projections 15 extending interiorly from the inner surface of the annular member 8 and into the opening therethrough. These projections may be easily and simply formed by off-setting suitable portions of the material of member 8 sufficiently at the desired points by a stamping operation, so that the projections 15 will engage between threads 3 on the neck 2 of the connector. It is readily apparent that these projections will not interfere with the proper positioning of the annular member 8 and at the same time will provide sufficient restraint to prevent the member 8 from undesirably sliding or falling off the threaded neck 2 of the connector.

Among many possible modifications that may be made in the shape and form of the annular member 8, are the following modifications illustrated in the drawings. As shown in Fig. 3 the annular member 8 may comprise an annular ring having its inner portion flanged outwardly somewhat axially to provide shank 13, and having the projections 15 offset inwardly of its inner periphery. In Fig. 4 the annular member 8 is illustrated as comprising an annular ring having an annular rabbeted portion on one side so as to provide the annular flange or shank 13 adapted to seat between the wall 110 surrounding the opening 7 and the neck 2 of the connector, and an outer portion 12 beyond flange 13 adapted to abut against a side of the wall 6. In Fig. 5 the member 8 is illustrated as having a ring-like form, 115 the ring, however, being hollow and split circumferentially. The ends do not meet and one end 12 is adapted to abut against the outer surface of the wall 6 surrounding the opening 7 and the other end 13 is adapted to seat within the opening 7 between the periphery of the opening and the neck 2 of the connector and to function similar to shank 13 of the other modifications. The surface 9 of the ring 8 120

away from the wall is adapted to abut against the abutment strip 4 of the connector, and its inner periphery is adapted to contact the neck 2 of the connector. In Fig. 6 the annular member 8 is illustrated as comprising a ring of sheet-steel, or similar material, and comprises an inner portion bent axially to a certain extent, as at 13, to extend somewhat within the opening 7 between the periphery of the wall 6 about the opening and the neck 2 of the connector, and an outer portion 12 larger than opening 7. In this modification the inner-most edge of member 8 may be adapted to engage between the threads 3 on the neck 2 so as to serve the same function as is served by projections 15 in the other modifications. In Fig. 7 the member 8 is shown to comprise an annular member having an outer portion or head 12' larger than the opening 7 and adapted to engage against one side of the wall 6 about opening 7, and an inner portion comprising an annular shank 13' smaller than said portion 12', and adapted to extend into the opening 7 between the periphery of the opening and the neck 2 of the connector. This member 8 may be fashioned in a solid piece or may be fashioned from a sheet of metal folded upon itself as illustrated in the figure at 16.

Many other modifications in the form and shape of the member 8 may be made without departing from the scope of my invention. For instance, it has been found that the member 8 may comprise a plain annular ring, circular in cross-section, of such size that it is adapted on one side to contact the wall about the opening and on its other side to contact the abutment strip 4 of the connector, and also to extend to a certain extent interiorly of opening 7 around the neck of the connector sufficiently to prevent undesirable movement of the parts.

To adapt a connector for mounting in a larger sized opening and to mount it firmly and securely in place therein by means of my improved adapter, I first take my annular member 8 and place it upon the neck 2 of the connector so that it abuts against abutment flange 4. I then place the connector in the opening 7 of the wall 6 with the shank 13 of the annular member 8 seated

within the opening 7, and then take nut 14 and adjust it upon the neck 2 of the connector from the opposite side of the opening 55 until it binds against the opposite side of the wall with the desired firmness. My connector is now suitably secured and mounted in the opening as desired.

In place of a lock nut 14 any other suitable devices may be used for accomplishing the functions performed by this element. My invention moreover is not limited to use with connectors or conduits or cable having external threads, and it is to be understood 65 that member 8 may be mounted either on the outside or on the inside of the wall opening, as desired.

What I claim is:

1. The combination with a wall having an 70 opening, of a connector having a peripheral flange and a threaded neck, an expansible washer on said neck and extending into said opening, said washer and flange having a tapered surface engagement, and means comprising a nut adjustable on said neck for pressing said washer and flange together to expand said washer against the periphery of said wall opening.

2. The combination with a wall having an 80 opening, of a connector having a peripheral flange and a threaded neck, an expansible washer on said neck and having a portion of greater diameter than said opening and a reduced shank portion adapted to seat within 85 said opening, said washer and flange having a tapered surface engagement, and means comprising a nut adjustable on said neck for pressing said washer and flange together to expand said washer against the 90 periphery of said wall opening.

3. The combination with a wall having an opening, of a connector having a peripheral flange and a threaded neck, an expansible washer on said neck and extending into said 95 opening, said washer presenting a tapered surface against said flange, and means comprising a nut adjustable on said neck for pressing said washer and flange together to expand said washer against the periphery of 100 said wall opening.

This specification signed and witnessed this second day of May, 1921.

GEORGE C. THOMAS, JR.
